GRAPPLING DEVICE

Ellis H. Spiegl, Salinas, Calif.

Application March 17, 1933, Serial No. 661,234

5 Claims. (Cl. 294—67)

The invention, generally, relates to means for grappling and hoisting relatively large and heavy bodies. More particularly, the invention relates to a device for use in hoisting containers, the device being so constructed as to enable the lifting of relatively large and heavily loaded containers and to maintain the containers in substantially neutral equilibrium while being lifted.

The device of my invention is adaptable for use in many environments, such as in lifting relatively large containers of ice and the like from platforms to conveyors or for hoisting crates of more or less unwieldy sizes. The device has been designed, however, with particular reference to the hoisting of relatively large and heavy lettuce crates and is especially suitable for such use.

It is an object of my invention to provide a simple yet rugged grappling device which enables hoisting of relatively large and heavy bodies while maintaining the same in substantially neutral equilibrium during lifting operations.

Another object of the invention is to provide a grappling device which is readily and easily placed into engagement with a load and also readily disengageable therefrom.

A still further object of the invention is to provide a durable yet inexpensively manufactured device of the aforementioned character.

Other objects of the invention, together with some of the advantageous features thereof, will appear from the following description of the preferred embodiment of the invention which is illustrated in the accompanying drawings.

Referring to the drawings:

Figure 1 is a plan of an embodiment of the invention, illustrated in operative position, for lifting a container.

Figure 2 is an elevation of the embodiment shown in Figure 1 and taken on the line 2—2 thereof.

Figure 3 is a plan of a modified embodiment of the invention.

In its preferred form, the grappling device of my invention preferably comprises a truss supporting a plurality of spaced guides, a pair of opposed body engaging elements slidably mounted in the guides, together with means for sliding the opposed elements of each pair of body engaging elements into engagement with opposite sides of a body and at spaced points thereon whereby the body can be lifted and maintained in substantially neutral equilibrium while being hoisted.

As illustrated in Figure 1 of the drawings, I

provide a truss, generally designated by the reference numeral 11, which includes a pair of spaced, longitudinally-extending beams 12 and 13, as well as braces or tie rods 14, 16, 17 and 18. A ring 19 conveniently is provided at the junction of the tie rods, that is, at a point substantially at the center of the truss, for receiving cables or other connections of a hoisting mechanism, not shown.

The truss 11 carries a plurality of spaced guides 21 and 22 which span beams 12 and 13 and, while I have illustrated but two guides, it is to be understood that additional guides, together with associated parts, can be employed without departing from the spirit and scope of the invention. Spanning the guides 21 and 22, and preferably disposed equidistantly from the beams 12 and 13, is a longitudinally-extending, rotatable member 23 which conveniently is journaled in bearings 24 and 26 mounted on the guides 21 and 22 respectively.

In accordance with the invention, a pair of opposed body engaging elements 27 and 28 are slidably mounted in each guide 21 and 22, the opposed elements of each pair being adapted to be moved into and out of engagement with opposite sides 29 and 31 of a body desired to be hoisted. It is to be observed that inasmuch as the guides 21 and 22 are spaced apart, the body engaging elements 27 and 28 are adapted to engage the opposite sides of a body at spaced points. Moreover, the device is constructed of such dimensions and the guides and associated body engaging elements are so spaced that upon engagement of a body and a hoisting thereof the body will be maintained in substantially neutral equilibrium during hoisting operations and hence, in the event an open container is being lifted, the contents of the container will not be displaced or spilled.

To effect movement of each element 27 and 28 of each opposed pair of elements, so as to place the same into engagement with opposite sides of a body and to release the same from the body, I provide a plurality of toggles, generally designated by the reference numeral 32, each of which includes toggle links 33 and 34. The links 33 conveniently are pivotally connected to the rotatable member 23, while the links 34 are pivotally connected to links 33 as well as to collars 35 mounted upon the body engaging elements 27 and 28, see Figure 1 of the drawings. Upon a rotation of the member 23 in one direction, the toggles 32 effect movement of the opposed elements 27 and 28 in opposite directions and place the same into engagement with opposite sides of a body to be hoisted. Conversely, upon a rotation of the mem-

ber 23 in the opposite direction, the direction of movement of the elements 27 and 28 of each pair thereof is reversed, and hence the elements are moved out of engagement with the body hoisted, 5 or, in other words, the body is released. It should be noted that the stroke of the toggles 32 is such, or the lengths 33 and 34 thereof as well as the body engaging elements 27 and 28 are constructed to such dimensions, that, with a given width of 10 body or container, and with the elements 27 and 28 in engagement with the opposite sides thereof, the links 33 and 34 of the toggles will assume a comparatively straight line position, as illustrated in Figure 1 of the drawings, and hence the toggles 15 will effectively lock the elements 27 and 28 in engaged position, or, in other words, in abutment with the opposite sides of the container.

For purposes of illustration only, I have shown the grappling device of my invention as applied 20 to an open top container 36 which is of the character disclosed in my copending application Serial No. 653,222, filed January 24, 1933, and entitled "Gathering apparatus and method". The container 36 includes bounding margins preferably 25 constructed of angle irons 37 which are co-extensive with the length and width of the container, and the container is reinforced with suitable rods, such as a plurality of spaced, transversely arranged T-straps 38. In the container illustrated 30 in Figure 1 of the drawings, I have shown three transverse T-straps 38, one adjacent each longitudinal extremity of the container and one at the center thereof. The grappling device of my invention preferably is constructed to such size 35 that it substantially spans the outer T-straps, as shown. With this size of grappling device a pair of opposed body-engaging elements 27 and 28 engages the container at opposite sides thereof and underneath the longitudinally-extending 40 angle irons 37, adjacent one outer T-strap 38, while another pair of opposed body-engaging elements 27 and 28 engages the container adjacent the other outer T-strap 38.

In order conveniently to enable ready movement or rotation of the member 23 and hence 45 place the body-engaging elements 27 and 28 into and out of engagement with the container 36, I provide a hand lever 39 which is fixedly secured to the member 23 adjacent one of the guides 21 50 or 22. With the container 36 upon a platform and before hoisting thereof, the grappling device can be centered over the container or placed in operative position and the hand lever then actuated to move the members 23, toggles 32, and 55 hence elements 27 and 28, into engagement with opposite sides of the container. The lever 39 is moved to its fullest extent in the direction which places the elements 27 and 28 into engagement, so that the lengths 33 and 34 assume a straight 60 line position. The cable or other line of a hoisting mechanism is then affixed to the device by attaching the same to the ring 19 of the truss, and the hoisting operation is begun. Upon reaching the level desired and depositing the hoisted 65 container, the grappling device is released. In order to effect a release of the device from a position below the hoisted container, as, for example, from the platform from which the container has been lifted, I have provided a cable 41 70 which is connected to the hand lever 39 and which passes over a pulley 42 conveniently mounted on a standard 43 affixed to the truss 11 of the device. The cable 41 can be made to any given length and preferably is of such length as to 75 extend between the levels of hoisting operations.

Accordingly, an operator upon the platform from 80 which the container has been lifted, in order to release the grappling device, is required merely to pull upon the cable 41 to actuate the lever 39 in the opposite direction from which it has been theretofore moved. Actuation of the lever in such direction reverses the movement of the body-engaging elements 27 and 28 to disengage the same from the container or, in other words to release the container.

In Figure 3 of the drawings I have illustrated a modified embodiment of the grappling device of my invention. This modification has been especially designed and is particularly suitable for use in hoisting a plurality of bodies such as containers simultaneously. In general, the modified embodiment is similar in all respects to the embodiment illustrated in Figures 1 and 2 of the drawings. However, it is to be noted that in the modification shown in Figure 3 of the drawings, the truss 11 so supports or so carries the guides 22, together with the associated opposed body-engaging elements 27 and 28, that each body or container 36 or a plurality of the same is engaged by at least one body-engaging element. It is to 100 be further observed that all of the opposed body-engaging elements 27 and 28 are actuated simultaneously and in one operation so as to grasp or release a plurality of containers simultaneously. This actuation of the several body-engaging elements is effected by the movement of the lever 39 which in turn causes movement of the rotatable member 23 and consequently actuation of the several toggles 32 which are connected through toggle links 33 and 34 with each element of the pair 105 of opposed body-engaging elements, all as described hereinabove in connection with the embodiment illustrated in Figures 1 and 2 of the drawings. In the embodiment shown in Figure 3, I have illustrated the device in position for use in hoisting two containers 36 arranged end to end in abutting relationship, the body-engaging elements 27 and 28 of the grappling device being placed into and withdrawn from engagement with the sides 29 and 31 of each 110 of the containers. If desired, but one pair of opposed body-engaging elements can be utilized for each container, rather than two or more elements per container.

While I have illustrated the preferred embodiment of the invention in the accompanying drawings, it is to be understood that I am not to be limited to the embodiment shown, as my invention, as defined in the appended claims, can be embodied in a plurality and variety of forms.

I claim:

1. A grappling device for use in hoisting bodies, said device comprising a truss including a plurality of spaced, longitudinally-extending beams, a plurality of guides connected across said beams, a movable member spanning said guides, a pair of opposed body engaging elements slidably mounted in each of said guides, toggles connecting each pair of said elements to said movable member, and means for moving said member to 135 actuate said toggles and to cause opposed elements of each of said pair of elements to engage opposite sides of a body to be lifted.

2. A grappling device for use in hoisting bodies, said device comprising a frame, a pair of spaced 145 guides on said frame, a movable member on said frame and spanning said guides, a pair of opposed body-engaging elements slidably mounted in said guides, toggle links connecting each pair of said elements to said movable member; and means for 150

- moving said member to actuate said toggle links and to cause opposed elements of each of said pair of elements to be moved so as to engage opposite sides of a body to be lifted at spaced points thereon. 5
3. A grappling device for use in hoisting bodies, said device comprising a truss, a ring carried by said truss and to which hoisting mechanism can be connected, a plurality of spaced guides on said 10 truss, a pair of opposed body-engaging elements slidably mounted on each of said guides, a movable member journaled in said truss, toggles connecting said movable member to each pair of said opposed elements; actuation of said toggles causing movement of each pair of opposed elements whereby opposite sides of a body can be engaged and disengaged by said elements at spaced points on the body, and means for moving said member to actuate said toggles. 15
- 20 4. A grappling device for use in hoisting a plurality of bodies of predetermined widths and lengths, said device comprising a truss spanning said bodies, a plurality of pairs of spaced guides carried by said truss; one pair of guides being sup- 25
- ported over each body to be hoisted, a pair of opposed body-engaging elements slidably mounted in each of said guides, a movable member spanning said guides, toggles connecting each pair of said elements to said movable member, and means for moving said member to actuate said toggles and to cause opposed body-engaging elements of each pair to engage opposite sides of each body to be hoisted. 80
5. A grappling device for use in hoisting a plurality of bodies of predetermined width and length, said device comprising a frame including a plurality of spaced, longitudinally extending beams spanning said bodies, a plurality of guides connected across said beams, a movable member spanning said guides, a pair of opposed body-engaging elements slidably mounted in each of said guides, toggles connecting each pair of said elements to said movable member, and means for moving said member to actuate said toggles and to cause opposed elements of each pair thereof to engage opposite sides of each of the bodies to be hoisted. 85
